UNITED STATES PATENT OFFICE.

HARVEY M. ARONSON, OF PITTSBURGH, PENNSYLVANIA.

CODING TYPEWRITER.

Application filed February 10, 1926. Serial No. 87,268.

The invention relates to coding typewriters for automatically coding and decoding messages written in the usual way. It has for its principal object, the provision of an improved form of machine of comparatively simple construction, which will automatically translate, into a practically undecipherable code, subject matter written in the usual way, and which can be similarly employed to decode the messages. The invention is shown and described as applied to a typewriter of the cylinder type, such for instance, as the "Hammond", but it will be understood that the invention is not limited to cylinder machines, or to machines in which the power applied to the keys by the operator actuates the mechanism, as the parts, under the control of the operator, may be motor driven. One embodiment of the invention, and of its method of use, is illustrated in the accompanying drawings wherein:

Figure 1 is a perspective view of a typewriter with the coding device applied thereto. Fig. 2 is a diagrammatic perspective view showing the working parts of the apparatus in connection with two of the keys of the keyboard. Fig. 3 is a perspective view, partly in section, showing the parts in a different position. Fig. 4 is a perspective detail view of two of the parts, one of which is broken away. Fig. 5 is a detail plan view of one of the parts. And Fig. 6 is a diagrammatic view illustrative of the principal of operation of the machine, and of its method of use, in connection with a sample code (namely +1-2+2-3).

The standard cylinder machine, to which the present invention is preferably applied, employs a type ring mounted to oscillate around a vertical axis, with a striking or impressing member opposite the operative position of the ring and an interposed ribbon and the paper which is to be imprinted. The striking of any key swings the type ring so that the character on the ring, corresponding to that on the key, moves to position opposite the striking member which then moves forward when the key is released and strikes the back of the paper. The positioning of the type ring is governed by stop pins, which are pushed up by the keys and determine the angle through which the type ring is swung. In order to limit the extent of the angle through which the type ring is swung, such movement occurs

in two directions from a central position, one half of the keys of the keyboard swinging the type ring in one direction, and the other half of the keys swinging it in the other direction. This machine is well known in the art, so that only a brief description is necessary in order to indicate its general characteristics.

The present machine, in its preferred embodiment, as later described more fully, involves a relatively simple modification of the foregoing cylinder machine. Briefly stated, the improved machine is provided with a plurality of similar type rings placed one above the other on a supporting cylinder, and each adjustable around the axis of oscillation of such cylinder, so that each may occupy a plurality of different angular positions corresponding in number to the number of characters on the rings. The cylinder is also mounted for movement up and down in a series of steps, so that any one of the rings may be brought to the level of the striking or impressing device, the other rings being at such time in inoperative positions. An automatic raising and lowering device for the cylinder is provided, arranged so as to be given a step-by-step movement by the actuation of the keys. With the apparatus, as thus arranged, the actuation of the keys shifts the type rings first up and then down in a continuously recurring cycle, and each in turn acts to imprint one of its characters upon the paper. For instance, with four type rings and starting with the upper ring in position opposite the striking hammer, the actuation of a key will cause a character on this ring (corresponding to the key struck) to be impressed on the paper. On the actuation of a second key, the type cylinder will be raised so as to bring the next ring below up to operative position, and a character on this ring will then be used to print. The actuation of a third key and a fourth key, will similarly bring the third and fourth rings into action, after which the movement of the type cylinder will be reversed, and it will be lowered step-by-step bringing into action successively the three rings above the bottom one. This brings the cylinder to starting position, and this cycle will be repeated as long as the operation of the keys continues.

If each ring is in what may be termed its normal position, that is, a position such

that when any key is struck, the character brought to printing position is that on the key, the foregoing operation would give a printed page exactly the same as if only the single type ring of a standard cylinder machine were used, but as heretofore indicated, each of the rings is adjustable circumferentially, and in using the machine for code work, each ring is adjusted either backward or forward from its normal position, so that the characters printed by each ring are out of correspondence with the keys struck, and a practically undecipherable text is produced, unless the code is known.

In order to decode a text of this character, all that is necessary is to set the rings on the machine in positions the reverse of those used in coding, and when the coded text is typed, the original uncoded text is the result.

The principle of the machine will be readily apparent by reference to Fig. 6, wherein the four type rings are designated by the reference numerals 1, 2, 3, 4, and the keys of the key board by the numeral 5.

A fifth ring 6 is also shown above the keys merely to illustrate the so-called normal position, such fifth ring not being present in the actual machine of Figs. 1 to 4. These type rings are shown as developed; i. e., straightened out into a plane so that all the characters show, and the characters, for simplicity of illustration, are in alphabetical order, and limited to twenty-six in number, corresponding to the keyboard, but it will be understood that in an actual machine, the number of characters will correspond in order and number to those on a standard typewriter, and that the arrangement of the characters on the keyboard will correspond to those on a standard keyboard.

If the four rings 1, 2, 3 and 4 were all adjusted to normal position, namely that of the ring 6, the actuation of the keys would give a text corresponding throughout to the letters of the keys. To give a code message, the rings are all adjusted from the central normal position 6. To illustrate, the code $+1-2+2-3$ is selected. Proceeding in accordance with this code, the top ring 1 is adjusted one step or space to the left to the position illustrated; the second ring 2 is adjusted two steps to the right to the position shown; the third ring 3 is adjusted two steps to the left to the position shown, and the fourth ring 4 is adjusted three steps to the right to the position shown. Assume that the term patent law patent law (two words repeated to show divergence when coded) is to be coded. Striking the key *p* gives the printed letter *q* from the first ring 1; the next key *a* struck gives the printed letter *y* from the second ring 2; the next key *t* struck gives the printed letter *v* from the third ring 3; the next key *e* struck gives the printed letter *b* from the fourth

ring 4; the next key *n* struck gives the printed letter *p* from the third ring 3, etc., the term patent law patent law, as completely coded, reading "qyvbpr myy mcrflv icu". In actual coding, the spacing between the words would, of course, be omitted. The rings are brought into action, as heretofore referred to, in a continuously recurring cycle, in the order 1, 2, 3, 4, 3, 2, 1, 2, 3, 4, 3, 2, etc. the number of possible code combinations, when four rings are employed, is so great that the possibility of decoding without the key is practically negligible. Further, this number of possible combinations may be magnified to any desired extent by increasing the number of rings. In order to decode a message made in accordance with the code $+1-2+2-3$, as above described, it is only necessary to reset the rings reversely, and typewrite the coded message. Such setting for the code given would be $-1+2-2+3$. With the rings so set, the writing of the coded phrase "qyvbpr myy mcrflv icu" gives the decoded phrase patent law patent law.

With the foregoing explanation of the principle involved, the mechanism of the machine, as illustrated will be readily understood. Referring to Fig. 1; 1, 2, 3 and 4 are the type rings heretofore referred to, 5 is the keyboard, two of whose keys 7 and 8 only are shown in Fig. 2; 9 is the base of the machine, 10 is the ribbon, behind which is the paper 11 to be imprinted and one of the rolls 12 for feeding the paper up and down, the other roll, as well as a number of the usual typewriter details having nothing to do with the present invention, not being shown. It will also be understood that the parts 11 and 12 are carried on the usual carriage mounted for movement step-by-step transversely of the machine to carry the paper past the printing or impressing device.

As indicated in Figs. 2 and 3, the type rings 1, 2, 3 and 4, are carried upon a cylinder or type drum 13, which in turn is carried by and attached to the tubular shaft or tube 14 so that it moves vertically therewith when the shaft is given such movement. This tubular shaft is splined in the sleeve 15, which latter is swivelled in the frame member 16 (Fig. 3). The sleeve has at its upper end the plate 17 extended at one end to provide the finger 18, and provided with the pair of shoulders 19, 19, as indicated in Fig. 5. The plate is also provided with an extension 20 carrying the rod 21, which extends upward into the perforation 22 in the cylinder 13.

The finger 18 is turned to position the cylinder by means of the keys as indicated in Fig. 2, two only of such keys being shown. The keys are pivoted at 23 and 24, and are all extended beneath the curved plates 25 and

26 carried by the rock shaft 27, and normally held in lower position by springs 28. The rock shaft also carries a pair of arms 29 and 30, which engage the shoulders 19, 19 on the plate 17. When any key is pressed down, therefore, it swings the plate 17 laterally and turns the cylinder, either one way or the other. The extent to which the cylinder is turned, is governed by the stop pins 31, 32, etc., guided in the rings 33 and 34 carried by the framework of the machine. The end of each of the keys 7, 8, etc., engages one of these pins, and when the key is depressed, or struck the corresponding pin is raised, so that its end projects above the ring 34 and acts as a stop for the finger 18. The pins are held down by the springs 35, so that they move down to inoperative position when the keys are released. The location of the pins is of course, coordinated with the position of the type rings 1, 2, 3 and 4 on the cylinder 13, so that, when any key is struck, the cylinder is stopped with the corresponding character on one of the rings in printing position, such position being opposite the striker or hammer 36 (Fig. 3) located at the rear side of the cylinder back of the paper 11 and ribbon 10. After a key is struck and the cylinder positioned, the hammer is moved forward sharply upon the release of the keys and strikes the paper, carrying it and the ribbon against the type character on one of the type rings. The mechanism for actuating the striker or hammer in timed relation with the actuation of the keys is well known in the art, and for the sake of clearness in the showing of other parts, is not illustrated. One half of the keys 7, 8, etc., are arranged to swing the cylinder 13 in one direction and the other half to swing it in the other direction. The range of the swing in each direction is 180 degrees, so that the entire circumference of each of the type rings 1, 2, 3 and 4 is utilized, being provided with the same number of characters as there are keys. The upper ring 1 is preferably provided with two rows of letters, one being small and the other capitals, and when the machine is used as an ordinary non-coding typewriter, only this one ring is used, just as in the ordinary cylinder machine, which has the two rows of type on the one ring. When the machine is thus used for non-coding purposes with the single ring in service, it is of course necessary to disconnect the device (later described) for bringing the rings 2, 3 and 4 into service, and provide the machine with the usual shifting device (not shown) employed in a cylinder machine for shifting from small type to capitals.

The rings 1, 2, 3 and 4 are mounted on the cylinder 13 for circular adjustment and each is provided with a set of locking notches 37 corresponding in number to the number of

type characters on the faces of the rings. The rings are held in adjusted positions by the four catches 38 held in locking position by the springs 39.

The tubular shaft 14 which carries the cylinder 13 at its upper end, is supported for oscillation on the shaft 40, anti-friction bearings 41, 41 being interposed between the cups 42, 42, at the ends of the tubular shaft 14, and the cones 43, 43 threaded onto the shaft 40.

The shaft 40, carrying with it the shaft 14 and cylinder 13, is moved up and down, step-by-step, by the lever 44, pivoted on the pin 45 carried by the post 46, such lever being forked and slotted, as indicated in Figs. 2 and 3, and engaging the pins 47 projecting from the collar 48 threaded on the shaft 40. The outer end of the lever is provided with an adjustable counterweight 49 for balancing the weight of the shaft 40 and the parts carried thereby. The lower end of the shaft 40 is steadied and guided in the base plate 50 of the machine by the sleeve 51 which is threaded onto the shaft, and has a snug sliding fit in the opening through the plate.

The lever 44 is itself oscillated up and down about the pin 45, by means of a cam 52, mounted for rotation on the shaft 53 and provided with the groove 54, which engages a pin 55 projecting laterally from the lever. The shaft 53 carries a ratchet member 56, splined thereto, and a second ratchet member 57, loose on the shaft, and provided at its end with the spur gear 58. The member 56 is pressed yieldingly against the member 57 by a spring 56^a. The member 57 is rotated back and forth, to give the cam an intermittent forward movement, by means of the rack 59, which engages the gear 58. The proportions are such, that each reciprocation of the rack gives the cam 52 a rotation of 60 degrees, so that the shaft 40 and type cylinder is raised in three steps as the cam moves through 180 degrees, and is then lowered in three steps as the cam moves through a further arc of 180 degrees. A half rotation of the cam from the position shown in Fig. 3 to that shown in Fig. 2 carries the cylinder from its lowest position (Fig. 3) with the type ring 1 opposite the hammer 36 to its highest position (Fig. 2), with the type ring 4 opposite the hammer, thus bringing characters on the rings 1, 2, 3 and 4 successively into operative or printing position. A further half rotation of the cam in three steps then brings the cylinder from its highest position (Fig. 2) to its lowest position (Fig. 3), again successively bringing the type on the rings 3, 2 and 1 into printing position opposite the hammer 36. It will thus be seen, that the reciprocation of the rack 59 in timed relation with the operation of the keys will bring the type rings successively into printing posi-

tion in a continuously recurring cycle, the order of use of the rings starting with the position of Fig. 3, being 1, 2, 3, 4, 3, 2, 1, 2, 3, 4, 3, 2, 1, etc., as long as the operation of the machine is continued.

The means for reciprocating the rack 59 in timed relation with the actuation of the keys will be seen by reference to Fig. 2. The keys 7, 8, etc., all pass beneath a curved bar 60, which bar is mounted for rocking movement on pins 61 journalled in the framework of the machine. Keyed upon one of the pins 61 is a crank 62, provided at its end with a laterally projecting pin 63 engaging a loop 64 at the upper end of the rack 59. The rack is suitably guided for vertical movement in the frame of the machine, by means, not shown, and is returned to its upper position by the spring 65, after each downward movement, the spring being attached at its lower end to the pin 63 and at its upper end to a suitable fixed point (not shown) on the frame of the machine. It will be seen, that the striking of any of the keys causes a reciprocation of the rack, the downward movement of the rack running the ratchet member 57 backward with respect to the ratchet member 56, and the upward movement of the rack by the spring 65 serving to rotate the member 56, and with it, the shaft 53 and cam 52. The parts are so proportioned that each reciprocation of the rack rotates the shaft 53 a sixth part of a whole revolution, the actuation of three keys thus serving to shift the cam from the position of Fig. 3 to that of Fig. 2.

Referring again to the diagram of Fig. 6, and the sample code +1-2+2-3, and phrase patent law patent law, there used for illustration, the operation of the machine is as follows, starting with the parts in the position of Fig. 3, with the cylinder 13 in the lowermost of its four positions. The four type rings are first set to correspond to the code; the ring 1 being to the left one character or notch, the second ring 2 being shifted to the right two characters, the third ring 3 being shifted to the left two notches, and the fourth ring 4 being shifted to the right three notches. The rings will now occupy the positions with respect to normal position, as shown in Fig. 6, and are locked in such positions by the catches 38. If now the key bearing the letter *p* is pressed down, on the keyboard, one of the pins 31 is raised by the end of the key (Fig. 2), and the key also swings the plate 25 up, rocking the shaft 27, so that one of the arms 29 swings the plate 17 and cylinder until the finger 18 strikes the end of the pin 31. This brings the letter *q* on the type ring to printing position opposite the hammer 36, since the type ring is now out of normal position and *q* occupies the position normally occupied by the character *p* (Fig. 6). The

downward movement of the key performs a third function of moving the rack 59 down, this being accomplished through the intermediary of the bar 60 (engaged by the end of the key) and the crank 62. The key, having performed the functions above set forth, is now released. This causes the forward movement of the hammer or striker 36 (Fig. 3) to engage the paper opposite the letter *q* and cause the printing of such letter, the mechanism whereby the actuation of the striker is secured upon the release of each key being well known in the art, and not being shown. The release of the key also permits the plate 25 to be moved downward by the spring 28, and the lever 29 is swung back to starting position, so that the plate 17 and cylinder 13 are also moved back to starting position. The release of the key also results in the raising of the cylinder 13 one step to bring the second type ring 2 to the level of the striker 36. When the key is released, the bar 60 swings down, due to the spring 65 which raises the rack 59, rotating the cam 52 from the position of Fig. 3, through an arc of sixty degrees, and raising the shaft 40, and with it the cylinder 13, and the type rings. The next letter of the message is *a* and when this key is pressed down, the letter *y* is brought to printing position, as indicated by reference to Fig. 6, the second type ring being adjusted two characters to the right of normal position in accordance with the second figure, —2, of the code. After this character is printed, the release of the key brings the third type ring 3 into position opposite the striker or hammer 36, and the actuation of the next key *t* causes the movement of the character *v* to printing position. The release of this key brings the fourth ring 4 to printing position and the actuation of the key *e* causes the movement of the character *b* to printing position. The cam 52 is now in the position of Fig. 2, and when the key *e* is released and the character *b* printed, the further rotation of the cam, causes the lowering of the cylinder and type rings one step, thus bringing the ring 3 again to printing position. The key actuated at this time is *n*, which brings the letter *p* to printing position. The foregoing is sufficient to indicate the cycle without further detailed description, the rings being shifted up and down by the cam in a continuously recurring cycle in the order 1, 2, 3, 4, 3, 2, 1, 2, 3, 4, 3, 2, 1, etc. By reference to the diagram of Fig. 6, it will readily be seen that the actuation of the remaining keys T law patent law, necessary to complete the message, patent law patent law will actuate the type "r myy mcrflv icu", thus completing the code message "qyvbpr myy mcrfly icu". In order to decipher the message on the machine, or in a corresponding one, the

- setting of the type rings at the code positions $+1-2+2-3$ is reversed, so that such rings occupy the positions $-1+2-2+3$, respectively. That is, the ring 1 is moved two spaces to the right of the position shown in Fig. 6; the ring 2 is moved four spaces to the left from the position shown; the ring 3 is moved four spaces to the right from the position shown; and the ring 4 is moved six spaces to the left from the position shown. The type rings should now be positioned so that they occupy the same vertical positions as those occupied when the coding of the message was started. That is the ring 1 should be at the level of the striker 36. If now, the keys are operated in accordance with the code message, "qyvbpr myy merfly icu", the decoded message patent law patent law will be printed.
- As indicated heretofore, the machine has been, for the sake of clearness, illustrated and described in its simplest and most rudimentary form, and it will be understood that, in its commercial form, a number of refinements and additions will be provided. The usual keyboard and characters of the standard machine will be used, and the type rings changed accordingly. A shifting device, to permit the use of the upper ring with both the capitals and the small letters will also be used, as heretofore referred to. It will also be desirable to use a space blank on each of the type rings (with a corresponding key in the keyboard) to provide for spacing the words in decoding the message, the space key being used in coding the message and decoding it in the same manner as the keys bearing the characters. The actuation of the space key in coding, will, of course, in most cases, give characters in the coded message, and the spaces which do appear will be at the wrong places, but in decoding, the spaces will all appear at their proper places, thus facilitating the reading of the message.
- What I claim is:
1. In combination in a coding typewriter, a type drum, having its axis vertical, mounted for vertical and rotary movement and having a plurality of perforations through its wall at different points around its circumference and at different levels, a plurality of type rings each carrying a set of type fitting around the drum one above the other, and each having upon its outer face a series of characters and upon its rear side a series of recesses, a plurality of catches carried by the drum having fingers projecting through said perforations in the wall of the drum and adapted to engage said recesses in the type rings and hold them in any desired position of circumferential adjustment, a set of keys, means governed by the successive actuation of the keys for shifting the drum and the plurality of rings carried thereby up and down, so as to bring them one after another to a level at which they are operative for printing, and means also operated by the successive actuation of the keys for shifting the drum circumferentially to printing positions corresponding to the keys actuated. 70
  2. In combination in a coding typewriter having a supporting frame, a vertical shaft, bearing means threaded thereon for vertical adjustment, a tube journaled on said bearing means, a type drum carried by and secured to the tube, a sleeve surrounding the tube and having splined engagement therewith, means for swiveling said sleeve upon the supporting frame, sliding engaging means between the drum and sleeve, a plurality of type rings carried by the drum one above the other and adjustable circumferentially, a set of keys, means whereby said shaft and the type drum carried thereby is shifted vertically step by step by the actuation of the keys, and means also operated by the actuation of the keys for shifting said sleeve and with it the type drum circumferentially in accordance with the keys actuated. 80
  3. In combination in a coding typewriter, a supporting frame, a vertical shaft guided in the frame for up and down movement, a type drum on the shaft movable vertically therewith and rotatable with respect thereto, a plurality of type rings arranged one above the other on the drum and adjustable circumferentially, a counterweighted lever for moving the shaft up and down, a set of keys, means governed by the successive actuation of the keys for swinging said lever to move the shaft up and down, so as to bring the type rings one after the other to printing position, and means also operated by the successive actuation of the keys for shifting the drum with the type rings circumferentially to printing positions corresponding to the keys actuated. 90
  4. In combination in a coding typewriter, a supporting frame, a vertical shaft guided in the frame for up and down movement, a type drum on the shaft movable vertically therewith and rotatable with respect thereto, a plurality of type rings arranged one above the other on the drum and adjustable circumferentially, a counterweighted lever for moving the shaft up and down, a set of keys, means governed by the successive actuation of the keys for swinging said lever to move the shaft up and down, so as to bring the type rings one after the other to printing position, means whereby the shaft may be adjusted vertically with respect to said lever, and means also operated by the successive actuation of the keys for shifting the drum with the type rings circumferentially to printing positions corresponding to the keys actuated. 100
  5. In combination in a coding typewriter, a supporting frame, a vertical shaft guided in the frame for up and down movement, 110

- 6 a type drum on the shaft movable vertically therewith and rotatable with respect thereto, a plurality of type rings arranged one above the other on the drum and adjustable 45
 5 circumferentially, a lever pivoted upon the frame and having one end in operative engagement with the shaft for moving it up and down, a cam adjacent the lever having 50
 10 operative engagement therewith, a set of keys, means actuated by the keys for giving the cam a step by step movement of rotation, and means also operated by the successive actuation of the keys for shifting the 55
 15 drum with the type rings circumferentially to printing positions corresponding to the keys actuated.
6. In combination in a coding typewriter, a supporting frame, a vertical shaft guided in the frame for up and down movement, a type drum on the shaft movable vertically therewith and rotatable with respect thereto, a plurality of type rings arranged one above the other on the drum and adjustable 60
 20 circumferentially, a lever pivoted upon the frame and having one end in operative engagement with the shaft for moving it up and down, a cam at one side of the lever having a groove therein, a member projecting laterally from the lever and engaging said 65
 25 groove, means actuated by the keys for giving the cam a step by step movement of rotation, and means also operated by the successive actuation of the keys for shifting the 70
 30 drum with the type rings circumferentially to printing positions corresponding to the keys actuated.
7. In combination in a coding typewriter, a supporting frame, a vertical shaft guided in the frame for up and down movement, a type drum on the shaft movable vertically 75
 35 therewith and rotatable with respect thereto,
 40
- a plurality of type rings arranged one above the other on the drum and adjustable circumferentially, a lever pivoted upon the frame and having one end in operative engagement with the shaft for moving it up and down, a cam adjacent the lever having operative engagement therewith, a set of keys, means actuated by the keys and including a rack and pinion and a ratchet device for giving the cam a step by step movement of rotation, and means also operated by the successive actuation of the keys for shifting the drum with the type rings circumferentially to printing positions corresponding to the keys actuated.
8. In combination in a coding typewriter, a supporting frame, a vertical shaft guided in the frame for up and down movement, a type drum on the shaft movable vertically therewith and rotatable with respect thereto, a plurality of type rings arranged one above the other on the drum and adjustable circumferentially, a lever pivoted upon the frame and having one end in operative engagement with the shaft for moving it up and down, a cam adjacent the lever having operative engagement therewith, a set of keys, means actuated by the keys for giving the cam a step by step movement of rotation, means for counterbalancing the weight of said shaft and the parts carried thereby, and means also operated by the successive actuation of the keys for shifting the drum with the type rings circumferentially to printing positions corresponding to the keys actuated.

In testimony whereof, I have hereunto subscribed my name this 6th day of February, 1926.

HARVEY M. ARONSON.
